UNITED STATES PATENT OFFICE.

LOUIS STEINBERGER, OF BROOKLYN, NEW YORK.

STRAIN INSULATOR.

1,406,698.

Specification of Letters Patent. Patented Feb. 14, 1922.

Application filed December 10, 1918. Serial No. 266,052.

To all whom it may concern:

Be it known that I, LOUIS STEINBERGER, a citizen of the United States, and a resident of the borough of Brooklyn, county of 5 Kings, State of New York, have invented certain new and useful Improvements in Strain Insulators, of which the following is a specification.

My invention relates to strain insulators 10 provided with means for causing the insulator to flash over between the strain member connected to the line and said means and the strain member connected to ground.

One of the objects therefore of my invention 15 is to provide a strain insulator with a conducting member normally inactive but so situated as to receive the current under abnormal conditions to carry the same through the central portion of the insulator 20 and arc across to the terminals or strain members thus causing the current to spark across rather than break down the insulator internally.

Another object of the invention is to provide 25 a normally inactive electrical conductor within the body of an insulator to act as a redistributor of the electrical stresses thereby improving the value of the insulator.

Other objects will appear from the sub- 30 joined specification and claims.

Referring to the drawings:

Fig. 1 is a vertical section through the central portion of a strain insulator embodying my invention, the parts of the insulator 35 being shown in elevation.

Fig. 2 is a similar view of a strain insulator illustrating a modified construction also embodying my invention.

It is well known that in actual operation 40 the insulating material especially at the central portion of the insulator becomes heated and thereby the insulator loses in efficiency both electrically and mechanically. If the heat is permitted to continue for a certain 45 period of time the destruction of the insulator will follow.

The present invention is applicable to all insulators and especially to strain insulators, and the insulator structure is so formed that 50 the central portion thereof which heats rapidly, is provided with an electrical conductor extending therethrough and protruding therefrom which will permit the ready flow outwardly from the center of the insulator body of the heat generated since metal is a much better conductor of heat

than the insulating material, the electric conductor also providing a conductive path through the insulator for the flashover current between the strain members. 60

I will now describe the preferred form of insulator embodying the invention hereinabove referred to.

In the drawings, in which the same reference character indicates the same part in the several views:

A is an insulator body which may be formed of any suitable insulating material, but I prefer to use the insulating material well known in the art as electrose. B is 70 the integral strain member made of metal and C is a two part strain member also made of metal which is provided with the well known means for connecting the two parts together, namely, one of the projecting ends 75 10 of the two part strain member is provided with screw-threads which engage the screw threads in the socket 11 of the removable portion 12 of the two part strain member C. The sleeve 13 is screw-threaded 80 to the other projecting end 10' of the embedded portion of the strain member and to the abutting end 14 of the removable portion of the strain member. This means of connecting the two part insulator so that 85 said parts may also be removed is well known in the art and therefore does not require a more specific description.

The strain members are also of the type invented by me and consist of bridge members 90 embodying ring shaped portions 20 and 30, said rings bridging the upright or leg portions respectively of the two strain members. The body portion of the insulator is molded about the strain members after 95 they have been centered with respect to each other by bringing the ring portion of each insulator opposite each other so that the rims of the ring portions will be in direct alignment, leaving a uniform body of insulating 100 material between the rings.

The body of insulating material is molded about the assembled interlocked strain members as shown, so as to form the shape shown in the drawings in which the insulating material is molded around the leg portions of each strain member to form projections 25, 26, 27 (the fourth not shown in the drawings), and there is also a central radially projecting flange 50 extending 110 from the insulator body. Integral flanges 21 and 22 extend from the legs of the embedded

portions of the two part strain member C. These flanges abut the outer ends of the projecting portions 25 and 26 of the insulator body so as to protect the insulator body from engagement with the sleeve 13 and the fixed end of the socket portion 11 of the removable portion 12 of the two part strain member, thereby preventing injury to the insulator body when the removable portion 10 of the strain member is fastened to the embedded portion thereof.

A centrally disposed rod 40 provided with globular shaped ends 41 and 42 is positioned in a straight line extending through the ring 15 portions of the strain members and so arranged that when the insulator body is molded into the shape shown, around and about the strain members, the rod 40 will be molded into the central portion of the insulator body, the globular ends 41 and 42 only projecting out therefrom.

As will be readily understood, this metallic rod does not normally carry any electric current but should the voltage become high 25 enough, the rod will cause the insulator to flash over between the strain members and the ends of the metal rod, thereby protecting the insulator against puncture.

Referring to Fig. 2 showing a modified 30 form of my invention, the insulator body and the strain members are the same as heretofore described with respect to the embodiment of my invention as shown in Fig. 1, the difference being that instead of a solid 35 metal rod, I provide a metal tube 60 in a position similar to that assumed by the metal rod 40 as shown in Fig. 1. This metal tube is molded within the insulator body centrally thereof and is surrounded by the 40 ring portions of the strain members in the same relative position as shown in Fig. 1 with respect to the ring portions of the strain members and the metal rod 40. The tube 60 is as stated above, molded into its 45 position within the body of the insulator during its manufacture and extends outwardly only to the top and bottom surface of the insulator body. The tube is screw-threaded at 61 within the inner surface 50 thereof. Two rods 62 and 63 provided with globular shaped ends 64 and 65 and with screw-threaded shanks 66 and 67 are adjustably secured respectively to each end of the tube, the screw-threads of each of the 55 shanks engaging the screw-threads on the inner wall of the metal tube so that the positions of the rods may be adjusted with respect to each other, as will be readily understood from this description and from the 60 illustration in Fig. 2.

The tube 60 and the rods 62 and 63 when assembled in the position shown in Fig. 2, form in effect so far as electrical carrying capacity is concerned, a solid rod of metal 65 and as herein described this electrical con-

ductor may be adjusted with respect to its length and the adjustment may be made at both ends as readily seen.

By this construction means are provided for adjusting the sparking or arcing gap 70 to predetermined value.

As changes of construction could be made within the scope of my invention, it is intended that all matter contained in the above description or shown in the accompanying 75 drawings shall be interpreted as illustrative and not in a limiting sense.

Having now described my invention what I claim as new and desire to secure by Letters Patent is:

1. An insulator comprising a body of insulating material, strain members provided with centrally disposed portions embedded therein, the central portions of the strain members being ring shaped, said ring portions being situated opposite to each other, an electrical conductor passing through the body of the insulator and also through the ring portions of the strain members, the said electrical conductor being provided 80 with exposed globular projections at each end thereof.

2. An insulator comprising a body of insulating material, strain members provided with centrally disposed portions embedded 95 therein, the central portions of the strain members being ring shaped, said ring portions situated opposite to each other, an electrical conductor passing through the body of the insulator and also through the ring portions of the strain members, the said electrical conductor being provided with an exposed globular shaped end.

3. An insulator comprising a body of insulating material, strain members provided 105 with centrally disposed portions embedded therein, said body being provided with an electrical conducting member passing therethrough, said electrical conducting member also passing through the central portions of the strain members and means for adjusting the length of said conducting member.

4. An insulator comprising a body of insulating material, strain members provided with centrally disposed portions embedded 115 therein, said body being provided with an electrical conducting member passing therethrough, said electrical conducting member also passing through the central portions of the strain members and means for adjusting 120 the length of said conducting member at each end thereof.

5. An insulator comprising a body of insulating material, interlocking strain members provided with centrally disposed portions 125 molded therein, the central portions of the strain members situated opposite to each other, the said central portions being ring shaped, and an electrical conductor passing through the body of the insulator 130

- and also through the ring portions of the strain members, said conductor consisting of a metallic sleeve molded to the insulator body provided with screw threads on the 5 inner wall thereof, screw threaded plugs adjustably secured to the centrally arranged sleeve.
6. An insulator comprising a body of insulating material, interlocking strain members provided with centrally disposed portions molded therein, the central portions of the strain members situated opposite to each other, the said central portions being ring shaped, and an electrical conductor 10 passing through the body of the insulator and also through the ring portions of the strain members, said conductor consisting of a metallic sleeve molded to the insulator body, provided with screw threads on the 15 inner wall thereof, screw threaded plugs provided with globular shaped ends adjustably secured to the centrally arranged sleeve.
7. An insulator comprising a body of insulating material, strain members provided with centrally disposed portions embedded therein, said body of insulating material having an electrical conducting member passing therethrough, said conducting member also passing through the central portions of the strain members and means for 20 adjusting the length of said conducting member at each end thereof.
8. An insulator comprising a body of insulating material, strain members provided with centrally disposed portions embedded therein, said body of insulating material having an electrical conducting member passing therethrough, said conducting member also passing through the central portions of the strain members and means for adjusting the length of said conducting member at 25 each end thereof.
9. An insulator comprising a body of insulating material, strain members provided with centrally disposed portions embedded therein, said body of insulating material having an electrical conducting member passing therethrough, said conducting member having globular shaped ends and also 30 passing through the central portions of the strain members and means for adjusting the length of the said conducting member at each end thereof.

In witness whereof, I have hereunto set 55 my hand at the borough of Manhattan, city and State of New York, this fifth day of December, 1918.

LOUIS STEINBERGER.

In presence of—
ZITA M. GRAHAM.
